2,441,654

METHOD OF MAKING NECKTIES

Jack Weisbaum, Cincinnati, Ohio

Application November 25, 1944, Serial No. 565,113

5 Claims. (Cl. 2—146)

1

My invention relates to improvements in methods of making neckties of the type shown in my Patent Re. 20,942, and to mechanism for use in practicing said method. My invention also relates to improvements in the method set forth in my Patent No. 2,131,545. This application is a continuation in part of my copending application, now issued as Patent 2,378,671 of June 19, 1945.

In my Patent No. 2,131,545 I have described the steps which were necessary in the making of my four-fold tie as shown in my Reissue Patent No. 20,942. These steps involved cutting the blank, hemming the edges, positioning each blank singly in my embossing press and then folding and bar tacking the tie. I emphasized, in this patent, the essential step of positioning and locating the blank so that the creases would occur along proper lines. The hemmed edge of each blank was fitted within a recess in each female plate of the press and so positioning of each single blank was facilitated. A single blank unhemmed could not be accurately positioned. My present invention is directed toward improving and simplifying said method and makes possible a multi-ply blank precreasing operation.

In my copending application, now issued as Patent No. 2,378,671, I have described improvements in the steps of manufacture of my patented tie wherein the blank, provided with three precreased fold lines extending substantially throughout the length of the blank, divides the blank into four flaps of substantially equal width. This precreased blank is then folded in a very precise manner. A side flap is first folded over to form an edge fold between said side flap and a contiguous flap. The folded edge is then positioned so that it lies substantially in alignment with the precreased fold line of the opposite side flap. Spaced machine bar tack stitches are then inserted which extend through the outer flap of the blank and both layers forming the edge fold. The position for the bar tacks is indicated by a series of notches cut in the blank prior to precreasing or embossing. The bar tacked blank is then pulled inside out and the tie is ready for the finishing pressing.

My present invention contemplates this same procedure but is an improvement on the steps necessary to practice the method disclosed in my Patent 2,131,545, in that the individual hemming of each blank, essential to the accurate positioning of each single blank in the creasing or embossing press is avoided and a multi-blank oper-

ation is made possible, obviating the use of many pressing machines heretofore required.

By my new process I provide a deeper recess in the embossing press and I have found that a plurality of tie blanks (6 to 12) may be accurately positioned in the press and the precreasing operation carried out as rapidly as was formerly required for the precreasing of a single blank. If the blanks should be hemmed first, this precreasing in plural plies cannot be accomplished because there would be much greater thicknesses of material at the ends than in the middle. By precreasing a plural number of blanks prior to hemming, however, leaving the hem portions of the tie uncreased, the hemming can be readily accomplished after creasing.

Plural layers of cut tie blanks can be positioned as accurately as it was formerly possible to position a single cut and hemmed blank. Then the hemming operation is carried out on the precreased blanks.

Since the precreasing of each edge hemmed blank was formerly the bottleneck of the manufacturing operation, my discovery that by putting off the hemming operation until after precreasing, the blanks could then be pressed in plural layers, was a labor saving step of marked importance.

Further referring to my copending application 30 which has issued as Patent 2,378,671, I am able to emboss creases extending in from the side edges of the blanks which will obviate the necessity of cutting or snipping "indicating" notches in the blanks to indicate the position for the insertion of the bar tack stitches, thereby eliminating a laborious operation in the cutting department. I am also able to do this operation at the same time the precreased fold lines are formed.

40 The foregoing objects and other objects to which I will refer in the ensuing description, I accomplish by the procedure hereinafter set forth.

Referring to the drawings:

Figure 1 is a perspective view of a preferred 45 type of press for carrying out my novel procedure.

Figure 2 is a sectional view of the press along the line 2—2 of Figure 1, but with a plurality of tie blanks in position.

Figure 3 is a perspective view of a tie after 50 pressing.

Referring to the drawings, I have shown a pressing machine having a head 1 and buck 2, the head carrying the male creasing die 3, or pattern plate, and the buck carrying the female die 4.

The depth of the cut-out portion forming the female die 4 or pattern plate, is suitable for receiving from six to twelve cut blanks.

The depth of the male die 3 is such that it extends down into the recesses of the female die. The male die has a side wall 5 extending around the outside edges of the cut tie blank. Ribs 6 extend lengthwise of the die. The length of the ribs is as indicated in the figures, there being clearance areas 7 at the ends of the ribs so that when a series of cut tie blanks are precreased or embossed the end edges of the blanks are not creased, so that the folding over and hemming (usually done on a hemming machine) may be accomplished without difficulty.

In the method of making these ties previously practiced, prior to my invention, as described herein, and as set forth in my copending application, which has issued as Patent No. 2,378,671, the tie blanks were cut or snipped at spaced intervals along one side edge to indicate to the operator of the bar tacking machine the position for insertion of the bar tacks.

It is a feature of my invention that this cutting or snipping is no longer required. The male die is provided (as shown in Figure 1) with cross ribs 9 which extend in from the edge wall 5 and fit within recessed slots 10 in the female die.

The lengthwise ribs 6 fit within recesses 11 in the female die and in the setting up and operation of the press it is important that the head and buck be arranged so that the ribs 6 of the male die enter the recessed slots 11 of the female die with a straight downward movement so as not to cause dislocation of the blanks and to permit a sharp crease line. At the same time the ribs 9 enter the recesses 10 with a straight downward movement.

The sequence of operation in practicing my new method is as follows. First the cloth material is laid upon a table and plural layers are cut to the proper outline usually by means of an electrical cutter.

A stack of blanks is then built up on a table convenient to the operator of the press. He takes a plural number of blanks which in plural thickness are sufficiently stiff to handle as a unit and places them within the recesses of the female die on the buck. Figure 2 shows a plural number of tie blanks at 12, prior to the precreasing operation. It will be observed in Figure 3 that after the precreasing operation the blanks have the lengthwise crease lines 13 which form the guides for the folding of the blanks and lateral edge creases 14, which indicate the position for the insertion of the bar tacks.

The ties are then stacked up on the table and when a sufficient stack has been built up they are taken to the hemming department where, there being no creases at the end edges, the hemming of these edges can be conveniently carried out on hemming machines.

The hemmed tie blanks then proceed to the bar tacking department where the folding of each hemmed blank is as follows: A side flap is folded over to form an edge fold. This folded edge is

then folded over so that it lies in substantial alignment with the precreased fold line of the opposite side flap. The bar tack stitches are then inserted in alignment with the side creases 14. The ties are then pulled inside-out and they are ready for the final finish pressing.

Having thus described my invention, what I claim as new and desire to secure by Letters Patent is:

10. In preparing blanks for four fold ties of the character specified for a subsequent bar tacking operation, the method which consists in precreasing a plurality of cut out blanks in a single creasing operation with three lengthwise fold lines and spaced side edge lateral fold lines, the lengthwise fold lines terminating short of the ends of the blanks and the lateral fold lines extending over a side edge flap sufficiently to act as indicia for the subsequent bar tacking operation.

15. In preparing blanks for four fold ties of the character specified for a subsequent bar tacking operation, the method which consists in precreasing a plurality of cut out blanks in a single creasing operation with three lengthwise fold lines and spaced side edge lateral fold lines, the lengthwise fold lines terminating short of the ends of the blanks and the lateral fold lines extending over a side edge flap sufficiently to act as indicia for the subsequent bar tacking operation, and subsequently hemming the end edges of the blanks.

20. In preparing blanks for four fold ties of the character specified for a subsequent bar tacking operation, the method which consists in precreasing a plurality of cut out blanks in a single creasing operation with three lengthwise fold lines terminating short of the ends of the blanks to prepare the blanks for a subsequent folding and bar tacking operation.

25. In preparing blanks for four fold ties of the character specified for a subsequent bar tacking operation, the method which consists in precreasing a plurality of cut out blanks in a single creasing operation with three lengthwise fold lines terminating short of the ends of the blanks to prepare the blanks for a subsequent folding and bar tacking operation, and subsequently hemming the end edges of the blanks.

30. In preparing blanks for four fold ties of the character specified for a subsequent bar tacking operation, the method which consists in precreasing a plurality of blanks with lengthwise fold lines and spaced side edge lateral fold lines extending over a side edge flap sufficiently to act as indicia for the subsequent bar tacking operation.

35. JACK WEISBAUM.
